UNITED STATES PATENT OFFICE.

MAX HERSKOVITZ, OF CHICAGO, ILLINOIS.

DESIGN FOR A SUPPORT FOR INCANDESCENT MANTLES.

SPECIFICATION forming part of Design No. 34,086, dated February 12, 1901.

Application filed January 18, 1901. Serial No. 43,817. Term of patent 7 years.

To all whom it may concern:

Be it known that I, MAX HERSKOVITZ, a citizen of the United States, residing at Chicago, in the county of Cook and State of Illinois, have invented and produced a new and original Design for a Support for Incandescent Mantles; and I do declare the following to be a full, clear, and exact description of the same, reference being had to the accompanying drawings, forming a part thereof.

Figure 1 is a front elevation of a support for incandescent mantles, showing my new design. Fig. 2 is a side elevation of the same.

As shown in the drawings, the leading or material feature of my design consists of a frame composed of a round wire bent upon itself to form two substantially parallel members D in the same plane, each of which near

the end is bent inwardly, forming a shoulder B, and the end portions of which are also parallel and have notches C cut therein. Where the wire is bent upon itself, a downward bend A is formed about half-way between the two members D.

Having thus described my invention, what I claim as new, and desire to secure by Letters Patent, is—

The design for a support for incandescent mantles, substantially as herein shown and described.

In testimony whereof I affix my signature in presence of two witnesses.

MAX HERSKOVITZ.

Witnesses:

O. K. TREGO,
LENA G. SNOW.
